SPRING COVER

George W. Crabtree, Cleveland Heights, Ohio

Application March 2, 1935, Serial No. 9,099

5 Claims. (Cl. 267—37)

This invention relates to improvement in covers or casings for laminated vehicle springs, and the primary object of the same is to provide a leaf spring cover assembly of the jointed section type which is practical and efficient in service and which at the same time is relatively simple in construction and assemblage and capable of economical or low cost manufacture.

The present invention is concerned broadly with a spring cover assembly of the type illustrated and described in my copending application Serial No. 9,097, filed March 2, 1935 and deals particularly with an alternate type of cap member for the jointed box sections and means for detachably locking said member to said sections whereby the assembly is better adapted for certain types of vehicle springs.

In the drawing:

Figure 1 is a substantially central longitudinal sectional view of a spring cover constructed in accordance with the present invention shown applied to a vehicle spring;

Figure 2 is a perspective view, partly broken away, of the cover with the cap member suspended thereabove; and

Figure 3 is a fragmentary perspective view of the cover with the cap member in assembled position.

The assembly comprises a plurality of jointed body or box sections generally indicated at A, A¹, A², A³, A⁴, and a cap or cover section B. The body sections are substantially identical in construction except the first and last sections, which have their respective outer ends adapted to the spring contour at these points and to also snugly engage and retain a liner C in position in the cover. Considering for example, the sections A¹ and A², the one end of A¹ telescopes partly into the adjacent end of A², and at the bottom of the cover, the ends are formed with interfitting arcuate bearing portions 5 and 6, note Figure 1.

This construction provides in effect a ball or rocking joint at the lower part of the sections. The arcuate bearing portions may be struck from the center of the hinge at the top of the sections so as to provide true coacting bearing surfaces.

The upper free edges of the sections are preferably flanged, as at 7 and 7a, and at the point where these flanges telescope into one another, they are notched or recessed and the metal bent down against the side wall of the inner section, to thereby provide a series of hinge joints 8 in cooperative relation with the arcuate joints 5—6.

55 The cap member B is preferably of integral

or one-piece construction and is provided with side flanges 9 and 9a which are turned down to snugly engage over the side walls of the body sections. At spaced points along the length of the cover and preferably at approximately in line with the central portion of each box or body section, the cap member B is provided with lugs 10 each having a slot 11 therethrough; and the opposed side walls of each section have locking ears or tabs 12 punched outwardly therefrom and adapted to engage in the slots 11. It will be noted that when the cap B is locked in position on the box sections, the lugs 10 cover the openings resulting from formation of the tongues or tabs 12.

The cap member B is preferably provided with a series of notches or cut-out portions 13, 13' and 13a, 13a' in the region of the joints between the sections, to permit free flexing of the cap without becoming displaced or strained, a stiffening tab 20 or lug 14 being provided between the two pairs of opposed cut-out portions.

Formed transversely between each pair of lugs 14 is a reinforcing rib 15, which ribs prevent longitudinal buckling of the cap and ensure against 25 breakage across the cap at the hinge points.

The body sections A may first be assembled in the form of flat blanks and locked in assembled relation by striking the hinges 8 at the time the cover assembly is pressed into final 30 form. The assembly is then ready to be applied to a spring, which latter process will be obvious, it only being necessary to first apply the liner C with a coating of lubricant, then the box section A and finally the cap member B, the 35 flanges 9, 9a being spread until the ears 12 register with the slots 11, whereupon the said ears pass through the slots and may be bent over to lock the cap in position on the sections. The cap may be easily removed by bending back the 40 ears 12 and lifting lugs 10 up over said ears, and the body sections will thereupon be free for removal in the event of repairs to the spring or for other purposes.

It will be noted that with this type of cover 45 assembly there are no laterally projecting parts, such as snap-on beads or the like, and the cap is securely clenched in assembled position, thereby eliminating any possibility of displacement in handling or piling a number of covered 50 springs together and in service.

It will be understood that minor changes in construction and mode of fabricating and assembling may be adopted within the scope of the invention as defined by the appended claims. 55

I claim:

1. A cover for leaf springs comprising a plurality of substantially U-shaped body sections adapted to be inserted over three sides of a spring, said sections being arranged in partly telescoped relation and connected to one another to provide a series of hinge joints, and a cap for said sections; said cap being formed with side flanges having slotted lugs at spaced points along the cap, locking ears punched from the side walls of the sections and adapted to engage in said slots whereby the cap may be detachably locked to the sections, the cap between said lugs and adjacent the joints of the sections having the flanges thereof cut away to facilitate flexing of the cap.

2. A spring cover for leaf springs comprising a series of substantially U-shaped body sections proportioned to cover three sides of a laminated spring, said sections being overlapped throughout a portion of their length and pivotally connected to each other in said overlapped portion to provide a series of hinge joints permitting the sections to flex with respect to each other in response to spring movement, a one-piece cap for said sections formed with side flanges having slots therethrough at spaced points along the length of the cap, and locking ears carried by and projecting laterally from the side walls of said body sections adapted to engage in said slots for locking the cap to the body sections, said side flanges being cut away in the region of said hinge joints to facilitate flexing of the cap section.

3. A cover for leaf springs comprising a plurality of substantially U-shaped body sections adapted to be inserted over three sides of the spring, said sections being arranged in partly overlapped relation and pivotally connected to each other adjacent the free edges thereof in said overlapped portion to provide a series of hinge joints between the sections, a cap for said sections formed with side flanges and proportioned to have said side flanges embrace the outer side walls of the body sections, said side

flanges having a plurality of slots formed therein at spaced points with respect to the hinge joint between the body sections and locking ears arranged to project laterally from said side walls and engage in said slots, said flanges being cut away in the region of the hinge joints in the body section whereby the cap may be detachably locked to the body sections and flex therewith.

4. In a cover for leaf springs, a plurality of U-shaped sheet metal box sections having their contiguous ends arranged in telescoped relation and secured to one another to provide a series of hinge joints, the side walls of said sections at intermediate points with respect to said joints having the metal thereof punched outwardly in the form of locking ears, and a cap for said sections of one-piece formation, said cap being formed with depending side flanges adapted to embrace the side walls of the body section, said flanges having spaced slots therein adapted to register with said ears and being cut away intermediate said slots in the region of said hinge joints to permit the cap to flex as said body sections turn on said hinge joints.

5. In a cover for leaf springs, a plurality of sheet metal U-shaped sections arranged end to end and having their abutting ends pivoted to each other, the side walls of said sections adjacent the upper free edges thereof having the metal thereof punched outwardly to provide a rounded locking tab extending in a vertical plane normal to said sections, a one-piece cap for said sections provided with resilient side flanges arranged to overlap the upper edges of the side walls of said sections, said flanges provided with vertically extending slots proportioned to receive said locking tab and adapted to be resiliently forced over the rounded edges of said tab when moved into assembled position with said sections, said flanges cut away intermediate said slots in the region of the pivotal joints between the sections whereby the cap may flex above said pivotal connection in response to spring flexure.

GEORGE W. CRAETREE. 45
